Patented May 29, 1917.

Inventor:
J. H. Bunting

By E. S. Grooman, his atty.

UNITED STATES PATENT OFFICE.

JAMES H. BUNTING, OF NEW YORK, N. Y., ASSIGNOR TO SUSQUEHANNA SILK MILLS,
OF NEW YORK, N. Y.

DESIGN FOR BROCADE.

50,831.

Specification for Design.

Patented May 29, 1917.

Application filed March 27, 1917. Serial No. 157,833. Term of patent 3½ years.

To all whom it may concern:

Be it known that I, JAMES H. BUNTING, a citizen of the United States of America, residing at New York, in the county of New York and State of New York, have invented a certain new, original, and ornamental Design for Brocades, of which the following is a specification, reference being had therein to the accompanying drawing.

The figure is a plan view of a piece of brocade, showing my new design.

I claim:

The ornamental design for brocade as shown.

In testimony whereof I hereunto affix my signature.

JAMES H. BUNTING.
